(57) **CLAIM**

The ornamental design for a 5 in 1 locomotive brake service tool, as shown and described.

DESCRIPTION

FIG. 1 is a top front perspective view of a 5 in 1 locomotive brake service tool, showing my new design.

FIG. 2 is a right-side elevation view thereof;

FIG. 3 is a top plan view thereof;

FIG. 4 is a front elevation view thereof, with the rear elevation view being a mirror image thereof;

FIG. 5 is a bottom plan view thereof;

FIG. 6 is a left elevation view thereof; and,

FIG. 7 is a bottom rear perspective view thereof.
